UNITED STATES PATENT OFFICE.

FREDERICK C. BLANCHARD, OF DETROIT, MICHIGAN.

LUBRICATOR.

Application filed March 26, 1923. Serial No. 627,592.

This invention aims to provide a novel and improved lubricator for automobile parts, and other machinery. The invention will be best understood by reference to the following description, when taken in connection with the accompanying drawings of one specific embodiment thereof, while its scope will be more particularly pointed out in the appended claims.

10 In the drawings:

Fig. 1 is a central, vertical sectional view of a lubricator exemplifying the invention, showing the lubricator in its normal closed position; and

15 Fig. 2 is a similar sectional view, showing the lubricator open, for filling.

Referring to the drawings, and to the embodiment of the invention which is selected for exemplification, there is shown a lubricator comprising a reservoir 4, having an inlet 5 and an outlet 6, the latter to be connected with the bearing to be lubricated. In the present example, the reservoir is formed as a part of a casing 7, conveniently stamped or drawn from sheet metal, and presenting at its lower end a threaded nipple 8 surrounding the outlet 6, and which may be screwed into an opening leading to the bearing.

30 To ensure an ample supply of lubricant between the bearing surfaces, and to carry away foreign substances and worn metal, as well as old, vitiated lubricant, provision is made for initial flooding of the bearing, followed by a relatively slow feeding of lubricant thereto. To this end, in the present embodiment, the outlet is normally closed by an outlet valve comprising a porous disk 9, conveniently formed of porous felt, which is normally seated upon a valve seat 10, herein presented by an inclined wall 11 having a frusto-conical form, which guides the valve toward its normal central position as it is closed.

45 The valve is normally seated, and prevents rapid escape of the oil therethrough, but when lifted to some such position as that illustrated in Fig. 2, permits a flooding of the bearing. On the other hand, when the valve is closed, a slow feeding of oil to the bearing is permitted, by reason of the fact that the disk is porous. The proportions and density of the felt disk are selected to suit the particular conditions under which 55 the lubricator is used, and if the rate of feed

is not correct, the disk may be removed and a different one substituted.

The inlet of the reservoir is shown normally closed and protected against the entrance of foreign matter by a suitable cover, herein a cap 12, conveniently formed of sheet metal and having a depending flange 13 normally disposed about the upper portion of the reservoir. Admission of air to the reservoir to facilitate the escape of lubricant therefrom may be accomplished by an air admission opening, such as a clearance space 14 between the cap and the body of the casing.

Herein, the operations of the cover and valve are co-ordinated, and suitable means are provided yieldingly to resist opening of the cover and valve, and to restore them to their closed positions after being opened. To those ends, in the present example, the cover and valve are connected to each other by a stem 15, which is secured to the cover, as by riveting at 16. An enlarged tapered, or frusto-conical formation 17 on the upper portion of the stem cooperates with the frusto-conical formation 11 to guide the cover and valve back to their normal position under the influence of a suitable spring. Herein, a helically coiled compression spring 18, encircling the stem, is seated at its upper end against a suitable abutment, herein an inturned flange 19 on the body of the casing, while the lower end of the spring is seated against an abutment presented by an outwardly directed flange 20 carried by the lower end of the stem. The valve is conveniently secured to the stem by a screw 21 extending through the valve, and threaded into the stem. In the present example, a washer 22, provided with perforations 23, presents a stop to limit descent of the valve under the influence of the spring which might otherwise compress the felt valve sufficiently to close the air vent 14. As shown in Fig. 1, the valve is somewhat compressed before the stop seats. Seepage of oil takes place through the felt valve, and the oil escapes through the perforations.

To operate the lubricator, the cover is first lifted from the position shown in Fig. 1 to some such position as that represented in Fig. 2, and lubricant is supplied to the reservoir. It follows that at first, the lubricant will run freely through the outlet to the bearing, thus flooding the latter. When the

bearing has taken up all the oil it can hold, as the supply of lubricant into the reservoir continues, the level will rise toward the top of the reservoir. The supply of lubricant should be discontinued when the reservoir is nearly or quite filled, after which the cover should be released, and the cover and valve allowed to close under the influence of the spring. The working part which is thus 10 lubricated can be started with the assurance of an ample supply of oil. Subsequently, during the operation, a slow feeding of oil takes place by way of the normal feeding device, herein by seepage through the felt 15 valve, the density and proportions of which are such as to permit the proper rate of feeding to suit the particular circumstances.

Having thus described one embodiment of the invention, but without limiting myself thereto, what I claim and desire by Letters 20 Patent to secure is:

1. A lubricator presenting a reservoir having an inlet and an outlet, a valve seat, an outlet valve comprising a pervious disk 25 the latter contacting with said seat, a cover for said inlet, and a connection between said valve and said cover to cause opening movement of said cover to be accompanied by opening movement of said valve.

2. A lubricator presenting a reservoir having an inlet and an outlet, a valve seat, an outlet valve comprising a pervious disk, the latter contacting with said seat, a cover 35 for said inlet, and a stem rigidly connected to said cover and to said valve to cause movement of one to be accompanied by like movement of the other.

3. A lubricator presenting a reservoir having an inlet and an outlet, a valve seat, an outlet valve comprising a pervious disk, the latter contacting with said seat, a cover 40 for said inlet, a connection between said valve and said cover to cause opening and closing movements of one to be accompanied by corresponding movements of the other, and a spring normally urging said disk against said seat.

4. A lubricator presenting a reservoir having an inlet and an outlet, a valve seat, an outlet valve comprising a pervious disk, the latter contacting with said seat, a cover 50 for said inlet, a stem secured to said cover, and fastening means securing said disk to said stem.

5. A lubricator presenting a reservoir having an inlet and an outlet, a valve seat, an outlet valve formed of pervious material, the latter contacting with said seat, a cover 55 for said inlet, and a spring normally urging said pervious material against said seat.

6. A lubricator presenting a reservoir having an inlet and an outlet, a valve seat, an outlet valve formed of pervious material, the latter contacting with said seat, a cover 65 for said inlet, and a spring normally urging

said pervious material against said seat and said cover toward its closed position.

7. A lubricator presenting a reservoir having an inlet and an outlet, a valve seat, an outlet valve comprising a compressible, 70 pervious disk, the latter contacting with said seat, and a spring normally urging said disk against said seat and compressing said pervious disk.

8. A lubricator presenting a reservoir having an inlet and an outlet, a valve seat, an outlet valve comprising a compressible, pervious disk seated upon said seat, a spring 75 normally urging said disk against said seat, and means to limit the seating movement of said disk under the influence of said spring.

9. A lubricator presenting a reservoir having an inlet and an outlet, a valve seat, an outlet valve formed of compressible pervious material seated against said seat, a cover 80 for said inlet normally presenting therewith an air vent for the entrance of air into said reservoir, a connection between said valve and said cover to cause closing movement of one to be accompanied by closing movement of the other, a spring normally urging said valve against said seat and said cover toward its closed position, and means to limit such closing movement under the influence of said spring thereby to 85 ensure the maintenance of said air vent.

10. A lubricator presenting a reservoir having an inlet and an outlet, a valve seat, an outlet valve comprising a compressible, pervious disk seated upon said seat, a spring 90 normally urging said disk against said seat, and means to limit the seating movement of said disk under the influence of said spring, said means having provision for the passage 95 of lubricant from said pervious disk to said outlet.

11. A lubricator presenting a reservoir having an inlet and an outlet, a valve seat, an outlet valve comprising a compressible, pervious disk seated upon said seat, a spring 100 normally urging said disk against said seat, and means to limit the seating movement of said disk under the influence of said spring, said means comprising a piece of impervious material having provision for the passage of 105 lubricant from said pervious disk to said outlet.

12. A lubricator presenting a reservoir having an inlet and an outlet, a valve seat, an outlet valve comprising a compressible, 110 pervious disk seated upon said seat, a spring normally urging said disk against said seat, and means to limit the seating movement of said disk under the influence of said spring, said means comprising a perforate disk providing for the passage of lubricant from 115 said pervious disk to said outlet.

In testimony whereof, I have signed my name to this specification.

FREDERICK C. BLANCHARD.
